UNITED STATES PATENT OFFICE.

JOHN G. BLESSING, OF OAK FOREST, ILLINOIS, ASSIGNOR, BY MESNE ASSIGNMENTS, TO AUTOMATIC ELECTRIC INC., OF CHICAGO, ILLINOIS, A CORPORATION OF DELAWARE.

PUNCHING DIE.

Application filed January 14, 1925. Serial No. 2,250.

The present invention relates in general to dies, but is concerned particularly with what are commonly known as punching or piercing dies.

5 One object of the invention lies in the design and construction of a die of this character which, with the same cutting member, can be actuated to cut or pierce different sized openings in a piece of material, the size of 10 the opening being dependent on the number of times the die is operated. This object is accomplished in the present disclosure by causing the material being punched to be automatically moved a definite distance 15 following each cutting operation.

Another feature lies in the provision of 20 means for moving the material variable predetermined distances independent of the cutting mechanism by operating the die in a distinctive manner, either once or a plurality of times, depending upon the space between the openings required, and for then again operating the die to punch or cut another opening in the material.

25 In order to enable a clear description of the invention to be made the same has been illustrated in the accompanying drawings in the form of a die for cutting notches in disks used in impulse transmitting devices, 30 such as illustrated in the co-pending application of Blessing, Serial No. 743,659, filed October 15, 1924.

The drawings comprising Figs. 1-4, inclusive, and 7, show various views of the die, 35 while Figs. 5 and 6 show a blank, before and after it has been cut.

Fig. 1 is a top view of the die; Fig. 2 is a side view; Fig. 3 is a bottom view; Fig. 4 is a view, partly in cross section, taken on line 4—4 of Fig. 3; and Fig. 7 is a top view of a portion of the die with screw 25 removed and handle 5 thrown back so that both cutting elements of the die may be clearly seen.

45 The die, in brief, consists of a mounting plate 1; a turn-table 8; die elements 35 and 7, the element 7 being attached to a hinged arm 5; and associated mechanism for rotating the turn-table, carrying the object being 50 cut, a definite distance following each cutting operation.

The construction and operation in detail is as follows:

Referring now particularly to Figs. 2, 3

and 4, a mounting plate 1 has attached to it 55 four legs 2, 2', 48 and 48'. These legs are secured in openings in the mounting plate 1 in the manner shown in Fig. 4, or may be secured in any other well known manner.

Two posts 18 and 18', having holes serving 60 as bearings for shaft 17, are secured to the upper side of plate 1. The handle 5 for operating the die is mounted on the shaft 17 between the posts 18 and 18' as clearly shown in Figs. 1 and 7.

65 The upper cutting element 7 of the die is fitted in a hole in the handle 5 and is held in its fixed position by a key 16 extending through the handle and through a portion of the cutting member. Secured to the plate 70 1 immediately under cutting member 7 is a spacer plate 26, and on this plate is positioned a case hardened plate 35 comprising the lower element of the die. These plates 26 and 35 are held in place by screws 15 and 75 15'.

A turn-table 8, shown in Figs. 1, 2 and 7, is provided with a downwardly extending shaft, which extends through an opening in the plate 1. The top of the turn-table 8 80 lies in a plane flush with the top of die element 35.

As will be evident from observation of 85 Figs. 5 and 6, the disks to be cut or perforated are provided with an opening in their center, as well as a slot 50 and a perforation 51. The turn-table 8 has accordingly been provided with upwardly extending projections 9, 10 and 34, which render the incorrect 90 positioning of the disk on the turn-table impossible, and also prevents the disk being turned independent of the turn-table. In

order to guard against the possibility of the disk tipping while it is being cut a spring member 6, fixed to the under side of the 95 handle 5, has its free end resting against the disk at a point very near where it is being perforated. The upward movement of the handle 5 is limited by the screw 25, and the 100 handle 5 is normally held in engagement with the screw 25 by a spring 45. This spring is shown in Fig. 4. The downward movement of the handle 5 to a point beyond that necessary to bring the die element 7 into proper cutting relation to die member 35 105 is prevented by the adjusting screw 13, which is held in its adjusted position by locking nut 14, as shown in Fig. 2.

It will be appreciated from the foregoing description that, to make a single perforation in a blank disk, the disk is merely placed on the turn-table 8 and the handle 5 operated downwardly as far as it will go. The amount of material cut away by this simple operation is indicated by a notch 52 in the disk shown in Fig. 6.

The foregoing description covers only so much of the construction of the die as is essential to enable a single perforation to be made in a blank disk. The various mechanisms required to cause the disk to be rotated automatically following each cutting operation will now be described.

On the under side of plate 1, secured to the shaft 39 of turn-table 8, is a ratchet wheel 11, which is held in fixed relation to shaft 39 by a key 27.

20 The legs 2 and 2' are slotted for a distance, as shown in Figs. 2 and 4, and in these openings is carried a horizontal bar 37, which is held in place by screws 31 and 31' through the medium of rollers 3 and 3'. 25 Riveted to the bar 37 is a post 47 provided with a pawl 42, which, as shown in Fig. 3, normally engages a tooth of the ratchet wheel 11.

A spring 12, having one end secured to leg 2 and the other end secured by means of member 38 to the horizontal bar 37, normally holds this bar in the position shown in Fig. 3.

As previously mentioned, the spring 45 in 35 the sleeve 24, which acts as a guide for arm 5, normally holds the handle 5 at its extreme uppermost position. This spring also holds the pin 44 in engagement with the handle 5.

40 Mounted on the horizontal bar 37 by means of screw 46 is a roller 40. This roller is in the path of pin 44 so that when the handle 5 is operated pin 44, on its downward movement, engages roller 40 causing the horizontal bar 37 to be shifted in the direction indicated by the arrow. The movement of the horizontal bar 37 is just sufficient to allow the pawl 42 to slide over one tooth of the ratchet wheel 11. When the handle 5 is released it and the pin 44 are 45 restored to their uppermost position by spring 45. As the pin 44 moves out of the path of roller 40, spring 12 becomes effective to restore the horizontal bar 37 to its initial position, and through the medium of pawl 42 rotates the ratchet wheel 11 and the turn-table 8 one step. As soon as the ratchet wheel 11 has rotated one step pawl 41 55 engages the next ratchet tooth to hold the wheel 11 in its advanced position.

60 In order to positively guard against any slight movement of the wheel 11 while the punching operation is actually taking place, an additional pawl 36 is provided. This pawl is mounted on a spring member 4 65 which is secured to post 20 which is secured

to a plate 32, and which, in turn, is secured to mounting plate 1 by screws 36 and 36'. A bracket 23, attached to the end of bar 37, is also connected with the spring member 4 by means of screw 21 so that any movement 70 of horizontal bar 37 is transmitted to the holding pawl 36, which is effective to firmly hold the wheel 11 in its proper position when the die is being operated. The spring member 4 is so tensioned that it assists the 75 spring 12.

From the foregoing description it will be appreciated that, each time the handle 5 is operated downward into engagement with the adjusting screw 13 and then permitted 80 to restore, the turn-table 8 will be rotated through the medium of pawl 42 and wheel 11 for the distance corresponding to the width of one tooth of the ratchet wheel. The distance of movement or rotation and the size of the cut made by the die is such that there is substantially no lap or space between two consecutive cuts. As a result 85 the size of the notch desired is merely determined by the number of times the die is operated. Fig. 6 shows a disk having a notch 52, which is the result of a single operation of the die, a notch 53 which is the result of five operations of the die, while the other notches shown are results of a still 90 larger number of operations.

The next feature to be explained has to do with the means whereby the disk may be rotated definite distances, independent of the perforating mechanism. This operation may 100 be accomplished in either of two ways. The pawl 42 may be so adjusted that it drops in the next tooth just as the die member 7 engages the disk, so that by operating the die to this point and releasing the handle the wheel 11 and turn-table are turned. The other method of rotating the table 8 is by seizing 105 the bracket 23 and directly operating the horizontal bar 37 as many times as required to rotate the wheel 11 the desired distance. 110

In certain instances it may prove advantageous to be able to rotate the turn-table quite a distance. This may be done by depressing the handle 5 just sufficient to permit pawl 42 to slide over the teeth of ratchet 115 wheel 11 without engaging sleeve 24. The wheel 11 may then be rotated as far as is desired in the direction of the arrow.

It will be noted that the top side of wheel 11 is slightly pitched downward from its axis. This provision is made so that the punchings which drop through plates 35, 26, and 1 onto wheel 11 slide to the edge thereof and drop off.

What is claimed is:

1. In a cutting die, a turn-table, a cutting member, a manually operable operating member for moving said cutting member from a normal to an alternate position and for positively locking said turn-table against 120 125 130

rotation in either direction, means for restoring said operating member following its operation, and means controlled by the operation and restoration of said operating member for moving said turn-table.

5 2. In a die, a turn-table, a cutting member, a manually operable operating member for moving said cutting member from a normal to an alternate position, a spring tensioned upon the operation of said member for causing its automatic restoration upon being released, and means controlled by the operation and restoration of said member for moving said turn-table a definite distance.

10 3. In a die, a manually operable operating member, a cutting member fixed to said operating member, a turn-table providing a support for the object to be cut by said cutting member, devices on said turn-table registering with perforations in the object to be cut to hold it in fixed relation to the turn-table, and mechanism rendered effective by the operation and restoration of said operating member to move said turn-table.

15 4. In combination with a cutting die and hand operated means for operating said die, a turn-table, and mechanism operated by said hand operated means for automatically turning said table a definite distance following each operation of said means, said mechanism also operable for turning said turn-table any desired extent independent of said means.

20 5. In a hand operated cutting or perforating die, a turn-table serving as a support for material to be cut, a pawl and ratchet device for turning said table, a hand lever pivoted at one end carrying a cutting member, mechanism rendered operative responsive to the manual operation and restoration of said lever for transmitting motion to said pawl and ratchet mechanism, and a second pawl cooperative with the ratchet of the first mechanism preventing retrograde movement of the turn-table.

25 6. In combination, a tool for perforating thin material, having key and frictional elements for maintaining the material in place together with means for re-positioning said material in the path of the cutting element of said tool following each cutting operation.

30 7. In a cutting die, a cutting member, a turn-table, mechanism operable from a normal to an alternate position to cause said cutting member to perform a cutting operation and upon its return to rotate said turn-table, and alternatively operable from normal to an intermediate position and back to rotate the turn-table only.

35 8. In a cutting die, a turn-table for supporting work to be cut, a cutting member, manually controlled interacting mechanism for causing the turn-table to rotate either before or after a cutting operation has taken

place and for regulating the distance of rotation of the turn-table between cutting operations at will.

9. In a cutting die, a cutting member, a turn-table, means controlled by said cutting member for rotating said table in one direction, means for preventing its rotation in the other direction, and means operable upon the operation of said cutting member for at times locking it against rotation in either direction.

10. In a cutting die, a cutting member, a turn-table, means controlled by said cutting member for rotating said table in one direction, means for preventing its rotation in the other direction, means operable upon the operation of said cutting member for at times locking it against rotation in either direction, and means for causing said cutting member to perform a cutting operation only while said last means is effective.

11. In a cutting die, a normally operated handle with a cutting member attached thereto, a pin normally held under spring tension against said handle, a spring tensioned shifting bar having a roller attached thereto in operative relation to said pin, an operating pawl attached to said bar normally engaging a tooth on the periphery of a turn-table containing material to be cut, means for moving said handle from a normal position to press said pin into engagement with said roller, and move said bar and said operating pawl, and to perform a cutting operation, means for releasing said handle to move it to an alternate position and to move said pin out of engagement of said roller, said bar moving said operating pawl to engage the next tooth on said wheel and under action of said shifting bar tensioning spring rotate said turn-table.

12. In a cutting die, a manually operated handle with a cutting member attached thereto, a turntable serving as a support for material to be cut, means for operating said handle from a normal to an alternate position to perform a cutting operation the size of said cutting member, means for releasing said handle and rotating said turn-table, means for repeatedly operating said handle to increase the size of the opening cut by the cutting member, and to rotate the turn-table after each operation.

13. In combination with a handle and a cutting die actuated thereby, a turn-table having key and frictional elements for maintaining material to be cut in place, together with means controlled by said handle for re-positioning said turn-table in the path of said cutting die following each operation of said handle.

In witness whereof, I hereunto subscribe my name this 8th day of January, A. D., 1925.

JOHN G. BLESSING.
